Primary Examiner—Jennifer Rivard*Assistant Examiner*—Angela J Lee(74) *Attorney, Agent, or Firm*—Alan U. Cantor; Mark S. Bicks; Alfred N. Goodman(57) **CLAIM**

The ornamental design for a multi-purpose electrical outlet, as shown and described.

DESCRIPTION

FIG. 1 is a perspective view of a multi-purpose electrical outlet in accordance with the invention;

FIG. 2 is a front elevational view thereof;

FIG. 3 is a rear elevational view thereof;

FIG. 4 is a top plan view thereof;

FIG. 5 is a bottom view thereof;

FIG. 6 is a left side elevational view thereof; and,

FIG. 7 is a right side elevational view thereof.

The broken lines immediately adjacent the shaded areas represent the bounds of the claimed design while all other broken lines are directed to environment and are for illustrative purposes only. The broken lines form no part of the claimed design.
